FLOOR MAT

Edward C. Matteson, Miami, Fla., assignor of
one-fourth to Wm. F. A. Buehner and one-
fourth to A. M. Weore, both of Miami, Fla.

Application July 26, 1932, Serial No. 624,858

6 Claims. (Cl. 40—140)

My invention relates to improvements in floor mats, and particularly to mats of this character made of rubber or other suitable material or composition, such as are used upon a floor, in front 5 of a door, upon a running board of an automobile, in elevators, and in other places where a floor mat is desired.

A primary object is to provide a mat having embodied therewith interchangeable letters, 10 names, numbers, figures, or other indicia, or any other inscriptive matter as may be desired, without changing the body of the mat or subjecting the same to complicated assembly operations. Another object is to provide a mat of this 15 character upon which any desired initial letters, numbers, figures, or other characters or indicia may be applied, removed, and interchanged, without the necessity of producing or using a new mat body for each particular combination 20 or assembly.

Still another object is to so construct the device that a mat body is provided with openings, such as square, circular, or any other desired 25 shape, to receive a block or blocks, which carry initial letters, numbers or figures, special designs, special inscriptions, or in fact any material, characters or indicia that it may be desired to display upon the floor mat.

Still another object is to provide a mat structure of a standard design, or of any desired design and size, that will have standardized openings provided therein to receive standardized blocks, of the same or any other desired material, carrying or showing individual letters, numbers, 30 figures, or other indicia as required and desired, to thereby present the blocks as interchangeable units assembled with the body of the mat to present the characters to be visible substantially a part of the mat, thereby doing away with the necessity for construction of a special mat for each individual showing or combination of characters, and making it possible to produce a mat having any desired combination, with the blocks interchangeable to change the combination, or any individual character, if and when desired.

With the above and other objects in view, which will be apparent to those skilled in the art, my invention includes certain basic features of construction and combinations of parts which will be hereinafter set forth in connection with the drawings.

In the drawings:

Figure 1 is a view in top plan of a mat constructed in accordance with my invention.

Fig. 2 is a longitudinal vertical sectional view substantially on line 2—2.

Fig. 3 is a view in top plan of one of the interchangeable blocks.

Fig. 4 is an enlarged fragmentary sectional view through the body of the mat to better show the manner of assembling the parts.

Fig. 5 is a top plan view showing a modified form and design of mat.

Fig. 6 is an enlarged fragmentary sectional view illustrating a modified construction.

Fig. 7 is a view in top plan of block illustrated in Fig. 6.

Fig. 8 is a fragmentary view in top plan illustrating another form.

Fig. 9 is an enlarged fragmentary sectional view through the structure illustrated in Fig. 8 to better show the mounting of the block.

Fig. 10 is a top plan view of the block.

As the parts are shown in Figs. 1 and 2, the mat is of the type ordinarily used upon automobile running boards, and in other like connections, and the body 1, which is of rubber or any other suitable material or composition, has a 20 frame 2 mounted around its edge and provided with a flange 3 outstanding to serve as a scuff-plate. While a metal frame is here illustrated, this is only intended to show one adaptation of the invention, and the mat can be made of any 25 desired shape, form, outline, and design, to suit the particular requirements and use to which the floor mat is to be put.

The body portion 1, as shown in Fig. 2, is preferably rather thin at its marginal edge 4, and is 30 thickened in its middle portion, as at 5 to give greater substance to the body. In this thickened portion 5 a plurality of openings 6 are formed in or through the material of the body, and flanges 7 are provided around the openings 6 at the top 35 thereof adjacent the wear surface of the body. These openings can be of any desired size and shape in outline; and, a single opening or any desired number of openings can be provided. While the illustration of Fig. 2 shows the body portion 40 as being thickened gradually from the marginal edge toward the portion having the openings 6 therethrough, the marginal portions might be made to be of substantially uniform thickness and the increased thickness can be provided only 45 around those portions through or in which the openings are to be provided.

In the present instance I have shown the openings as substantially square in plan, and the blocks 8 will be of corresponding shape and size. 50 These blocks 8 are, in the main, of a thickness to fit within the openings 6 with their upper marginal edges against the rim flanges 7 and the body portions then just filling out the remaining portions of the openings so that the lower side of each block is in substantially the same plane as the under side of the body portion 1.

As illustrated in Figs. 2 and 4, the blocks 8, and the openings 6, are slightly tapered from the lower face 9, as indicated at 10, and when the blocks 8 60

are fitted within the openings 6 they will hold by friction therein; however, under some circumstances and conditions it may be desirable to provide additional security for the blocks, and 5 with this in mind a bead or rib 11 can be provided entirely around the marginal face of the block, or upon a portion thereof, to be received and held in a correspondingly shaped groove 12 formed in the wall of the opening 6.

10 While the number, letter, figure, name, emblem, or other inscriptive matter or indicia can be shown upon the upper face 13 of the block 8 in any desired manner, in the present instance I have shown a letter "B", indicated at 14 as bossed 15 up or raised from the surface 13 a distance corresponding substantially to the thickness of the die flange 1, and in this way the letter is elevated and is disposed to be substantially a part of and in the same plane with the tread surface of the 20 body of the mat.

15 In Fig. 5 I have illustrated a different shape and form of mat in which a greater number of openings 6 are provided so that a proper name, as "Smith", or any other name, or word, or combination of figures, or other matter, requiring the use of 25 several characters, can be assembled to be shown on the face of the floor mat.

20 Referring to Figs. 6 and 7, the body 15 of the mat has the wall 16 of the opening 17 therein formed on a greater angle, and the rib and groove 25 are not employed. Such a construction will be particularly advantageous where the blocks are desired to be readily removable for frequent interchanging, as the frictional wedging will not be quite so secure and the blocks can be fitted into and removed from the openings with greater facility.

25 Referring now to the showing in Figs. 8, 9 and 10, the openings 18 are substantially circular and 40 the side walls are substantially parallel. The body portion 19 has a groove 20 formed around the wall of the openings 18 to receive the peripheral rib 21 provided on the circular block 22.

30 From the foregoing it will be seen that I have 45 provided a floor mat including one or more blocks carrying a letter or letters, a number or numbers, a name or emblem, or any other inscriptive matter or indicia, and have constructed the body of the mat for insertion of such blocks into or 50 upon the mat body in seats or openings provided thereon or therein, which seats or openings will hold the blocks in interchangeable, removable or replaceable fittings to thus be presented to 55 show the character or other matter, and to present the appearance of being substantially a unitary part of the body of the mat.

60 While I have herein shown and described only certain possible uses it will be appreciated that many changes and variations can be made in the form, construction, shape, design, assembly, and use of the floor mat, without departing from the spirit and scope of my invention.

I claim:

1. A floor mat comprising, a body portion hav-

ing openings therethrough, and blocks fitted interchangeably in the openings to have a portion exposed as a part of the surface of the body portion, said mat being made of resilient material and said blocks and the body portion within said 5 openings having interfitting rib and groove formations to hold the blocks against casual displacement in either direction.

2. A floor mat of resilient material comprising, a body portion having an opening therethrough, and a block having an indicia on one face thereof fitted through and to fill said opening and provided with interlocking rib and groove portions frictionally held in place with the body portion to present the indicia to be visible within the field of the tread surface of said body portion and to hold the block against casual displacement in either direction.

3. A floor mat comprising, a body of resilient material thickened in part and having an opening through the thickened part, and a block fitted removably through the opening and provided with interlocking rib and groove portions whereby the block is held against casual displacement in either direction with one face exposed in the 20 field of the tread surface of said body portion.

4. A floor mat comprising, a body portion of resilient material having an opening therethrough with the wall of the opening grooved peripherally, and a block of resilient material fitted removably through and to fill in and close 30 said opening and provided with a peripheral rib to fit within the groove of the body portion and hold said block against casual displacement in either direction from the opening.

5. A floor mat comprising, a flat body portion of resilient material having an opening therethrough with a rim flange around the opening at the tread face of the body portion, and a block of resilient material fitted through and 40 within the opening to substantially fill the lower portion of said opening and contact with said flange, said block being provided with a raised portion in the middle part thereof substantially the thickness of said flange to thus lie in the plane 45 of the tread face of the body portion, and said body portion and block having interfitting rib and groove formations engaging to hold the block against casual displacement from the opening.

6. A floor mat comprising, a body portion having an opening therethrough with the wall of the opening grooved peripherally in its middle portion, and a block fitted removably through and to fill and close said opening and provided with a peripheral rib around its middle portion to fit 50 within the groove of the body portion and hold said block against casual displacement in any direction from the opening, one of said members being sufficiently yieldable to insure a close fit of the rib within the groove and to yet allow 55 compression for ready manual placement and removal.

EDWARD C. MATTESON.
